SHEAR TYPE RAZOR

George I. Wahnish, Los Angeles, Calif.

Application May 3, 1947, Serial No. 746,673

3 Claims. (Cl. 30—43)

1

This invention relates to shaving devices or razors of the electrical or mechanical type wherein a cutting or shearing blade is moved relatively to a perforated plate to sever the hairs projecting through perforations in the plate.

In the type of electrically operated razor as known at the present time, the cutting of the hairs is done by rapidly moving a shearing head or blade back and forth across an apertured or perforated plate, said plate being referred to as a "guard" or "comb" and being interposed between the skin and the cutting or shearing head. The hairs to be sheared off, thus pass first through the apertures or perforations in the guard or comb and those portions of the hairs which protrude beyond the outer face of the guard or comb are sheared off by the rapid reciprocating or oscillating movements of the shearing blade or head. Since the guard or comb is interposed between the cutting instrumentality and the surface of the skin, it is apparent that if a satisfactory and relatively close shave is to be secured, the guard or comb must be made of extremely thin metal. The result is that such guards or combs are easily damaged, and rapidly wear out and require replacement. Moreover, to attain a satisfactory shaving operation, it is necessary that the cutting head or blade be constantly urged resiliently against the guard or comb, and for this reason springs are used for that purpose. Such springs are relatively light so as not to create excess friction between the cutting member and the guard and the result that when a tough beard is encountered the cutting member is often pushed away from the guard and unsatisfactory shaving results are obtained.

The use of a guard interposed between the skin and a cutting member was employed in an effort to obtain satisfactory shaving results without the possibility of cutting or abrading the skin and while an arrangement of that character is effective for the above-stated purpose, there is no doubt but that the optimum of shaving results is not secured by such an arrangement.

I have found that it is entirely possible to provide a cutting or shearing mechanism by means of which the cutting blade is placed outermost or immediately adjacent to the skin with the guard or comb located beyond the cutter, without causing the skin to be cut or damaged by the shaving operation and resulting in the attainment of greatly improved shaving results. I have further found that by such arrangement, a relatively thick guard plate or comb may be used so that replacement seldom, if ever, is re-

2

quired. With an arrangement as described above, a blade or cutting member of such form is used that the shaving operation constitutes also a honing operation for the cutting edge of the blade.

5 without imposing extraordinary wear on the guard or comb, so that the blade will always remain sharp and at maximum cutting efficiency.

The object, therefore, of the present invention is to provide a razor of the character described 10 having the facility for giving a close, extremely satisfactory shave for the toughest of beards; which will not cut or abrade the skin; which does not require repeated replacements of the blades or guards, in which the blade can be held 15 with firm, resilient pressure against the guard to insure maximum cutting efficiency, and with which other advantages are secured as will be readily apparent to those skilled in this art.

With these and other objects to be hereinafter 20 set forth, in view, I have devised the arrangement of parts set forth below and more particularly pointed out in the claims appended hereto.

In the accompanying drawing, wherein an illustrative embodiment of the invention is disclosed, Fig. 1 is a top plan view of a shaving device or razor, constructed in accordance with the invention; Fig. 2 is a side elevation of the same, showing the blade holder in its rearward position; Fig. 3 is a front elevation of the head of the razor; Fig. 4 is a transverse sectional view through the cutting head and associated parts of the razor, with the blade holder shown in its forward position; Fig. 5 is a perspective view, with a part broken away, of the blade mounting or carriage; Fig. 6 is a face view of the blade, and Fig. 7 is a sectional view, in perspective, of the body of the cutting head upon which the guard plate or comb is provided.

Referring to the drawing, 1 indicates the conventional casing or housing in which an electric motor, a spring motor, or other power source is contained. Such source of power may be of any of those now known and used in electric or mechanical razors and hence the details of the power unit are omitted in the drawing. At the top, the casing 1 is provided with a groove 2 in which the base portion of the body of the cutter head 3 is received and maintained by means of a set screw 4 or other suitable fastening element.

The cutter head 3 includes a base portion 5 which seats in the slot or groove 2 as above described. At the top, the base portion 5 is formed with a rearwardly extending horizontal flange 6, the upper surface of which constitutes a support 50 for the slidably mounted blade holder or car-

riage 7. At the rear end of the flange 6 is an upstanding wall 8 constituting a rear stop for the blade holder 7.

Extending forwardly of the base 5 of the cutter head 3 is a pair of spaced parallel flanges or plates 9 and 10. The uppermost of said plates, indicated at 9, constitutes a comb or hair-engaging element which receives and maintains the hairs, while a cutter blade 12 operative over the outer face of the plate 9, shears off the hairs. The plate 9 is rounded at its forward edge, as indicated at 13 and for a substantial portion of its area and adjacent to its forward edge, it is foraminous, or provided with a plurality of closely-spaced independent holes as indicated at 14. A space 11 is provided between the perforated plate 9 and the lower plate 10, such a space constituting a hair collection chamber for the severed hairs, and this space may, if desired, be closed by a removable cover which is not shown for clarity in illustration, but which may be used to confine the cut hairs in the space 11 during the shaving operation.

Extending rearwardly from the perforated plate 9 is a flange 15, serving as a guide for the blade-holder or mounting 7, now to be described. Said blade-holder consists of a channel-shaped member having a lower flange 16 provided with a hole 17 which receives the eccentric pin 18 at the end of the motor-driven drive shaft 19 of conventional form, and which extends through an opening 20 provided in the base portion 5 of the body of the cutter head. This engagement of the blade-holder by the pin 18 is such as to cause the blade-holder and the blade 12 carried by it to be oscillated so that the forward or cutting edge of the blade 12 is moved over the perforated portion of the plate 9 to shear off hairs protruding through the holes 14 in the plate. The blade-holder 7 also includes a top flange 21 provided with an inclined upper face 22 which constitutes a seat on which the blade 12 rests. The blade 12 is confined and prevented from endwise movement on said seat by means of end walls 23 on the seat 22, and the blade is restrained from forward movement relative to the seat 22, by means of lugs 24 at the front of the seat. The blade 12 is provided with notches 25 in its opposite ends to accommodate the lugs 24.

The blade 12 when placed upon the seat 22, is held against the same and has its forward cutting edge portion 27 pressed resiliently but firmly against the top face of the apertured plate 9, by means of a spring finger 26. In the drawing the finger 26 is shown as formed integrally with the blade-holder 7, but in actual commercial production said finger will probably be a separate element suitably attached to said blade-holder. The spring finger 26 extends forwardly and downwardly and holds the front cutting edge 27 of the blade against the perforated plate 9 with constant and uniform firmness to insure an effective shearing action between the blade 12 and plate 9, and as the blade is oscillated over the face of the plate 9 a honing action is also imparted to the sharp edge 27 of the blade so that the cutting edge thereof is constantly maintained in sharp condition. However, due to the effective shearing action secured as the blade is held in firm contact with the face of the plate 9 and is moved thereover, an extraordinarily sharp edge is not required on the blade 12.

The blade-holder 7 straddles the flange 15 and when the razor is operated, the blade 12 is caused, by the oscillating movement of its holder, to be

moved rapidly over the perforated plate 9 and it will shear off hairs projecting through the perforations 14. In using the razor, it is held with the blade next to the skin, or in other words, with the blade 12 interposed between the skin and the perforated plate 9. When held almost flat against the face, the hairs will enter the perforations 14 and will be sheared off by the blade 12 operating between the surface of the skin and the plate 9, the hairs being held in the perforations while the blade shears them off. Due to the fact that the cutting edge 27 of the blade 12 is maintained firmly against the outer face of the perforated plate 9, the cutting edge 27 will not cut or abrade despite the fact that the blade is held in direct contact with the skin but will provide an exceptionally smooth and close shave.

I have found that the provision of separate and independent holes or perforations 14 in the plate 9 is an important feature of the invention since the use of elongated slots, and particularly those which are open ended, is not conducive to a good shearing action since such slots allow the hairs to either flatten when being sheared or else move out of the slots altogether. Hence, the use of the separate minute holes or perforations 14 in which the hairs enter and are held during the shearing operation by a blade interposed between the surface of the skin and a co-operating shearing plate is of the essence of the present invention.

While I have described a single embodiment of the invention, it is obvious that various changes may be made in the illustrated structure without departing from the spirit of the invention. The change, shape and thickness of the blade may be varied, the means for resiliently holding the blade in firm contact with the surface of the perforated shearing plate may also be changed materially. While the perforated plate 9 is shown as flat, such plate and the blade co-operating with the same may be arcuate or curved and other modifications readily made. Hence, I do not wish to be understood as limiting the invention to the illustrated embodiment but intend that the same shall be comprehended as being within the scope of the claims appended hereto.

What I claim is:

- 50 1. In a razor of the character described, a head having a pair of spaced forwardly-extended flanges, one of said flanges being provided with a substantial area perforated with a plurality of separate, relatively tiny holes, the space between the flanges constituting a hair-collection chamber, a channel-shaped blade holder having an inclined outer face constituting a blade-seat, a blade clamped against the seat, said blade having an edge portion held against the outer face of the perforated flange and sliding moved over the outer face of said flange, means for slidably moving the blade holder, and a guide flange provided on the head for guiding the blade holder.
- 55 2. In a razor of the character described, a head having a forwardly extending flat flange having an area formed with a plurality of separate, relatively tiny, closely-spaced independent holes whereby said area is substantially foraminous, said head having a rearwardly extending flange constituting a support for a blade holder, a channel-shaped blade holder resting upon said support and slidably thereover, a seat on the outer face of the blade holder for supporting a
- 60 70 75 blade in an inclined position, said blade having

a cutting edge extending forwardly of the holder and held in contact with the outer face of the forwardly-extending perforated flange, means on the holder for urging the forward portion of the blade into resilient contact with the outer surface of the perforated flange, and means for slidably moving the blade holder on its support to thereby slidably move the cutting edge of the blade over the perforated area of the forwardly-extending flange.

3. In a razor, a head having a forwardly-extending flat plate having an area formed with a plurality of separate, relatively tiny, closely-spaced independent holes whereby said area is substantially foraminous, said head having a rearwardly-extending flange slidably receiving a blade-holder, a blade-holder having a channel fitting said flange and slidable thereon, the top of the blade-holder being inclined, a blade seated on said inclined top of the holder, said blade having a forward sharpened edge projecting beyond the front edge of the holder and held in contact with the outer face of the forwardly-

extending perforated plate, pressure means on the holder for urging the forward portion of the blade into resilient contact with the outer surface of the perforated plate, said pressure means consisting of a spring finger anchored at the rear end of the holder and having a free end exerting downward pressure on the forward part of the blade, and means for slidably moving the blade-holder on its support to thereby slidably move the cutting edge of the blade over the perforated area of the forwardly-extending plate.
